(57) CLAIM

The ornamental design for a center console fascia with transitional buttons for vehicle, as shown and described.

DESCRIPTION

FIG. 1 is a front, right perspective view of the center console fascia with transitional buttons for vehicle showing our new design in a first state;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is a front, right perspective view thereof in a second state in which the screen unit protrudes in the form of buttons at an upper portion of the screen unit;

FIG. 9 is a front view thereof;

FIG. 10 is a rear view thereof;

FIG. 11 is a left side view thereof;

FIG. 12 is a right side view thereof;

FIG. 13 is a top plan view thereof;

FIG. 14 is a bottom plan view thereof;

FIG. 15 is a front, right perspective view thereof in a third state in which the screen unit protrudes in the form of buttons at a lower portion of the screen unit;

FIG. 16 is a front view thereof;

FIG. 17 is a rear view thereof;

FIG. 18 is a left side view thereof;

FIG. 19 is a right side view thereof;

FIG. 20 is a top plan view thereof; and,

FIG. 21 is a bottom plan view thereof.

The broken lines depict portions of the center console fascia with transitional buttons for vehicle that form no part of the claimed design.

The center console includes a screen unit with transitional states of appearances. The transitional states of appearances sequentially change between the first, second and third states as illustrated in the drawings. The process or period in which the different states of appearances change do not form part of the claimed design.
